UNITED STATES PATENT OFFICE.

ALFRED B. ELLIS, OF MORAN, TEXAS.

ROTARY BIT.

1,411,772.

Specification of Letters Patent. Patented Apr. 4, 1922.

Application filed July 12, 1920. Serial No. 395,563.

To all whom it may concern:

Be it known that I, ALFRED B. ELLIS, a citizen of the United States, residing at Moran, in the county of Shackelford, State of Texas, have invented new and useful Improvements in Rotary Bits, of which the following is a specification.

This invention has to do with a rotary bit and more particularly with a rotary well 10 drilling bit. An object of the invention is to provide a device of this character which is simple, inexpensive to manufacture, and effective.

The present bit comprises, generally, a 15 body formed with sockets, cutters arranged in the sockets to extend from the body, and means for preventing displacement of the cutters from the sockets. The body is preferably a cast member provided with a joint 20 shank and is formed to securely and rigidly carry the cutters. The cutters, of which there are three in the particular bit herein set forth to disclose the invention, are comparatively small hard steel members suitably 25 sharpened or dressed. The means for holding the cutters in the body, or in the sockets, comprise pins arranged through the body and the cutters.

A feature of the bit provided by the present invention is its cheapness of manufacture 30 and its durability. The construction of the bit is such that the body portion can be of comparatively cheap construction, for instance, it may be an ordinary steel casting, 35 and the cutters, which must necessarily be made of comparatively expensive, or high grade, steel, can be made comparatively small and therefore comparatively inexpensively. Further, the fact that the cutters are removable 40 from the body permits of them being replaced when worn out thereby making it unnecessary to replace the entire bit as is usually necessary in devices of this character.

Another feature of the invention is the 45 construction which permits of the bit being easily and conveniently handled and repaired. The securing of the cutters in the sockets by means of pins permits of them being very easily removed, and the fact that 50 the cutters are comparatively small members permits of them being easily and conveniently handled when they have been removed from the body. This is particularly important as it greatly simplifies and facilitates 55 dressing of the cutters and thereby lends to economical drilling. Further, the fact that

the cutters are comparatively small and easy to handle, also permits of them being more easily and perfectly heat treated or tempered than ordinary bits of this character can be. 60

Another and noteworthy feature of the invention is the construction of the bit which allows it to be worked in mud, or the like, without becoming clogged, or without catching and accumulating mud. The body of the 65 bit is provided with suitable openings which permit of circulation of mud, or the like, through it and the cutters are carried so as to be separated, or suitably spaced, thereby eliminating pockets or corners such as are 70 liable to become clogged or filled with mud, or the like. In fact, the construction of the bit is such as to cause churning, or, circulation of mud rather than accumulation or collection of it. 75

Another important feature of the invention is the construction of the bit which permits of circulating water being supplied to the cutters close to their edges, or to where they are actually cutting. This is particularly important in that it assures of the cutters being kept clean and adds greatly to their effectiveness and to the circulation around the cutters and, in fact, around the entire bit. 85

Other objects and features of the invention will be best understood from the following detailed description of a preferred embodiment of the invention throughout which reference is had to the accompanying drawings 90 in which—

Fig. 1 is a front elevation of the cutter provided by the invention; Fig. 2 is a view of the cutter taken as indicated by line 2—2 on Fig. 1; Fig. 3 is a bottom plan view of the 95 cutter being a view taken as indicated by line 3—3 on Fig. 1; Fig. 4 is a bottom plan view of the body alone or without the cutters in place; Fig. 5 is a detailed sectional view of the lower portion of the bit being a view 100 taken as indicated by line 5—5 on Fig. 2; Fig. 6 is a detailed sectional view taken as indicated by line 6—6 on Fig. 1; Fig. 7 is a detailed sectional view taken as indicated by line 7—7 on Fig. 1, being a view showing 105 the arrangement of the reamer; Fig. 8 is a sectional view taken as indicated by line 8—8 on Fig. 3; and Fig. 9 is a view of a fish-tail cutter removed from the body.

Throughout the drawings numeral 10 designates the body of the bit which carries the cutters A, B and C and which is formed

with a suitable screw-threaded shank 13. The body 10 is preferably a cast steel member and it will be understood that the shank 13, which is preferably cast or formed integrally with the rest of the body, may be of a size and shape which will fit the particular drill pipe, or member, on which the bit is to be mounted. For instance, the shank 13 may either be formed with drill pipe threads, tapered tool joint threads, or it may be a 10 degree tapered shank, or the like, as circumstances may require. The body 10 is a comparatively flat broad member, being about twice as wide as it is thick, and is formed with suitable rounded corners, or edges, as clearly shown in the drawings. In the preferred form of the invention, the body is formed with vertical circulation openings or slots 14, as I will hereinafter term them, through it and is formed at its lower end 22 with recesses or sockets 15, 16 and 17 to carry the cutters A, B and C respectively. I herein refer to the circulation opening, or openings, as circulation slots to clearly distinguish them from the water holes 60 hereinlater described, and therefore it is to be understood that the invention is not limited to the circulation openings being specifically in the form of slots. The slots 14, of which there are two, in the body shown in the drawings extend completely through the body 10 and are preferably comparatively large. By the provision of the slots 14 in the body 10 it is possible to make the body comparatively heavy and strong and yet not make it bulky, or so that it will accumulate or gather mud, or the like, when in operation. The circulation slots may, of course, in practice be made of various shapes and sizes and may be formed at parts of the body where they will be most effective.

The socket 15, which carries the central cutter A, is located in the center of the body 10 and extends straight into the body, or in other words, is arranged to extend into body so that its sides or walls are parallel with the vertical or longitudinal axis of the body. The socket 15 is not as deep as the sockets 16 and 17 but is comparatively long and narrow and is arranged transversely of the body when considering it as viewed in Figs. 3, 4 and 6. The socket 15 is shaped to receive the shank 20, formed on the central cutter A so that the shoulder 21 formed on the cutter A will engage or bear against the lower end 22 of the body, in the manner shown throughout the drawings. To secure the shank 20 in the socket 15 a pin 23 is arranged through bores 24 and 25, in the body 10 and shank 20, respectively which are in register when the shank 20 is properly and completely in place in the socket 15. The pin 23 is preferably a driving fit in the bores 24 and 25 so that it can be removed if

necessary but so that it will not become displaced when the bit is in operation. This manner of removably mounting the cutter in the body is extremely simple, effective, and permits of inexpensive manufacture. 70 In Figs. 1, 2, 3 and 5 of the drawings the central bit A is shown as a diamond point bit and it is shown to be somewhat longer than the cutters B and C. It will be understood of course that any suitable type or 75 form of cutter A may be employed in the bit provided by the invention, for instance, what is known as a fish-tail bit such as is shown in Fig. 9 of the drawings, may be advantageously used in place of a diamond 80 point bit.

The socket 16, which is adapted to carry the shank 30 formed on cutter B, is formed in the bottom of the body 10 at one side of the socket 15, and preferably comparatively 85 close to the socket 15. The socket 16 is shaped to receive the shank 30 so that the shoulder 31 formed on the cutter B will engage or seat against the bottom 22 of the body 10, and a pin 33 is arranged through 90 bores 34 and 35 in the body 10 and shank 30, respectively, to hold the cutter B in place in the body 10, in the same manner as the pin 23 holds the cutter A in place.

The socket 17, which carries the shank 38 95 formed on the cutter C is formed in the bottom of the body 10 at somewhat of an angle, as clearly shown in Figs. 1 and 5, and so that the cutter C will be carried in a manner to cause its outermost portion or 100 tip to be a considerable distance beyond, or outwardly of, the body 10, as clearly shown in the drawings. Due to the socket 17 extending diagonally into the bottom of the body 10 it is preferred that the shoulder 40, 105 formed on the cutter C to engage the bottom of the body 10, be at an angle which will cause, or allow it, to properly engage the bottom 22 of the body 10. By forming the socket 17 in the body at an angle it is unnecessary to provide a curved or peculiarly shaped cutter in order that it may extend outwardly of the body, in fact, it is merely 110 necessary to provide a straight cutter such as is shown in the drawings. The cutter C 115 is retained in the socket 17 in the same manner as the cutters A and B are retained in the sockets 15 and 16, respectively, by a pin 42 arranged in bores 43 and 44 in the body 10 and shank 38, respectively. 120

It will be noted in the drawings that the cutters A, B and C are of different lengths, the cutter A being the longest and the cutter C being the shortest, and that the cutters are arranged to each cut at a different portion or to each have a different path, when the bit is in operation. Further, it will be noted that the cutters are arranged so that their paths somewhat overlap thereby causing the bit to make a complete cut from its 130

center to the outer edge or tip of the outer cutter C. The paths of the various cutters are indicated by the dotted lines in Fig. 3, wherein the dotted circle A' indicates the path of the cutter A, the dotted circles B' indicate the path of the cutter B, while the dotted circles C' indicate the path of the cutter C. In practice the fact that the cut is made by these independent, or entirely separate, cutters is of particular importance in that it allows the bit to take small cuts, or to take off small chips rather than causing it to take off large chips as results from the use of a bit having a continuous blade.

15 Further, the arrangement of the cutters so that they are of different lengths is of particular importance as this causes the two outer cutters, that is, the cutters B and C to operate or cut with particularly high efficiency because they have a hole to cut to, or in other words, because a hole is started for them by the central cutter A.

To facilitate in removing the cutters from the sockets, after the pins 23, 33 and 42 have been removed, suitable openings 50 are provided in the cutters, adjacent to the shoulders formed on them to engage the bottom 22 of the body 10, so that a suitable wedge can be arranged through them as indicated by the dotted line W in Fig. 8. It will be readily understood how the cutters can be very easily removed from the sockets by forcing the wedge into the openings 50.

Suitable holes 60 are formed longitudinally through the body 10 from the shank 13 to its end 22 so that water, or other liquid, can be effectively supplied to the cutters at times when it is desirable. The fact that the cutters are well spaced and comparatively short, or small, causes water discharging from the holes 60 to effectively reach the cutting edges of the tool. Further, the slots 14, in the body, also greatly assist in the circulation of liquid about the cutters as they allow, or, in fact, stimulate circulation of liquid or mud around and in the vicinity of the bit.

In the preferred form of bit a socket 61 is formed in the side of the body 10 to carry 50 a reamer 62. The reamer is provided so that the bit will drill a clean hole of a certain size. In the drawings the socket 61 is formed in the body 10 so that the reamer

can be arranged through it and to extend into one of the slots 14. With this arrangement the reamer can be very easily and effectively held against displacement by a pin 74 through it and so as to extend from it into the slot.

Having set forth a preferred form of my invention I do not wish to limit myself to the specific details hereinabove set forth but, rather, wish to reserve to myself any changes or variations that may appear to those skilled in the art or that may fall within the scope of the following claims.

Having described a preferred form of my invention, I claim:

1. In a rotary bit of the character described a body formed with sockets to carry cutters and a slot to allow circulation.
2. In a rotary bit of the character described, a body carrying cutters and having longitudinally disposed circulation slots.
3. In a rotary bit of the character described, a flat body carrying cutting parts at its outer end and having longitudinally disposed slots at its edge parts.
4. A bit of the character described embodying, a body having a circulation slot in it, a cutter carried centrally at the end of the body in a plane diametrically and longitudinally of the body, and a second cutter carried at the end of the body in spaced relation to the first mentioned cutter and at one side of the first mentioned cutter, the path of the second cutter overlapping and extending outward of the path of the first mentioned cutter.

5. A bit of the character described embodying, a body, a cutter carried centrally at the end of the body in a plane diametrically and longitudinally of the body, and a second cutter carried at the end of the body in spaced relation to the first mentioned cutter and at one side of the first mentioned cutter, the path of the second cutter overlapping and extending outward of the path of the first mentioned cutter.

In witness that I claim the foregoing I have hereunto subscribed my name this 2nd day of July, 1920.

ALFRED B. ELLIS.
